(57) **ABSTRACT**

Acoustic echo cancellation systems and methods are provided that can generate a continuous mask value that can be used as a gain of a non-linear processor. Communication between a loudspeaker and the non-linear processor can be utilized to adjust the threshold of the non-linear processor when the loudspeaker is active to assist in suppressing far end single talk leakage. The systems and methods can improve the removal of residual echo and therefore enhance the overall performance of the acoustic echo cancellation system.

MASK NON-LINEAR PROCESSOR FOR ACOUSTIC ECHO CANCELLATION

CROSS-REFERENCE TO RELATED APPLICATION

This application claims the benefit of and priority to U.S. Provisional Patent Application No. 63/260,750, filed on Aug. 31, 2021, the contents of which are incorporated herein in their entirety.

TECHNICAL FIELD

This application generally relates to a non-linear processor used in an acoustic echo cancellation system.

BACKGROUND

Conferencing environments, such as boardrooms, conferencing settings, and the like, can involve the use of microphones (including microphone arrays) for capturing sound from audio sources and loudspeakers for presenting audio from a remote location (also known as a far end). For example, persons in a conference room may be conducting a conference call with persons at a remote location. Typically, speech and sound from the conference room may be captured by microphones and transmitted to the remote location, while speech and sound from the remote location may be received and played on loudspeakers in the conference room. Multiple microphones may be used in order to optimally capture the speech and sound in the conference room.

However, the microphones may pick up the speech and sound from the remote location that is played on the loudspeakers. In this situation, the audio transmitted to the remote location may therefore include an echo, e.g., the speech and sound from the conference room as well as the speech and sound from the remote location. If there is no correction, the audio transmitted to the remote location may be low quality or unacceptable because of this echo. In particular, it would not be desirable for persons at the remote location to hear their own speech and sound. Typical acoustic echo cancellation systems utilize an adaptive filter, e.g., a finite impulse response filter, on the remote audio signal to generate a filtered signal that can be subtracted from the local microphone signal to remove linear echo.

SUMMARY

The techniques of this disclosure are directed to solving the above-noted problems by providing systems and methods that are designed to, among other things: (1) generate a continuous mask value that can be used as a gain of a non-linear processor, based on: an adaptation state of the adaptive filter, a coherence of a microphone signal and a filtered remote audio signal, and a comparison of the microphone signal and the filtered remote audio signal with respect to a threshold of the non-linear processor; (2) determine the adaptation state of the adaptive filter based on the microphone signal and the filtered remote audio signal using a convergence integrator; and (3) utilize communication between a loudspeaker and the non-linear processor to adjust the threshold of the non-linear processor when the loudspeaker is active to help suppress far end single talk leakage.

In an embodiment, a device may include at least one processor configured to adaptively filter, with an adaptive

filter, a remote audio signal to a filtered remote audio signal; adaptively filter, with an adaptive filter, a remote audio signal to a filtered remote audio signal; generate, with a non-linear processor, a mask value usable as a gain of the non-linear processor; multiply the mask value with an initial echo-cancelled audio signal to generate a final echo-cancelled audio signal; and output the final echo-cancelled audio signal. The generation of the mask value may be based on: the adaptation state of the adaptive filter, a coherence of the microphone signal and the filtered remote audio signal, and a comparison of the microphone signal and the filtered remote audio signal with respect to a threshold of the non-linear processor.

In another embodiment, a system may include a microphone, a loudspeaker, and at least one processor. The microphone and the loudspeaker may be located in the same housing. The at least one processor may be configured to estimate, with an estimator, an adaptation state of the adaptive filter based on a microphone signal and a filtered remote audio signal; and generate, with a non-linear processor, a mask value usable as a gain of the non-linear processor. The generation of the mask value may be based on: the adaptation state of the adaptive filter, the microphone signal, and the filtered remote audio signal.

These and other embodiments, and various permutations and aspects, will become apparent and be more fully understood from the following detailed description and accompanying drawings, which set forth illustrative embodiments that are indicative of the various ways in which the principles of the invention may be employed.

BRIEF DESCRIPTION OF THE DRAWINGS

FIG. 1 is a schematic diagram of a communication system including an acoustic echo cancellation system that includes an estimator and a non-linear processor, in accordance with some embodiments.

FIG. 2 is a flowchart illustrating operations for determining an adaptation state of an adaptive filter using the estimator of the acoustic echo cancellation system of FIG. 1, in accordance with some embodiments.

FIG. 3 is a flowchart illustrating operations for generating a mask value that can be used as a gain of the non-linear processor in the acoustic echo cancellation system of FIG. 1, in accordance with some embodiments.

FIG. 4 is a schematic diagram of a communication system including an acoustic echo cancellation system that includes an estimator, a non-linear processor, and communication between a loudspeaker and the non-linear processor, in accordance with some embodiments.

FIG. 5 is a flowchart illustrating operations for adjusting a threshold of the non-linear processor of FIG. 4 based on whether a state of the loudspeaker has changed and whether the loudspeaker is active, in accordance with some embodiments.

FIG. 6 is a flowchart illustrating operations for adjusting a threshold of the non-linear processor of FIG. 4 based on whether a level of the non-linear processor has changed and whether the loudspeaker is active, in accordance with some embodiments.

DETAILED DESCRIPTION

The systems and methods described herein can generate a continuous mask value that can be used as a gain of a non-linear processor. A non-linear processor can be utilized to remove residual echo that cannot be removed by an

adaptive filter, and to ultimately generate an echo-cancelled audio signal that can be transmitted back to the far end. The non-linear processor may calculate a gain to suppress the residual echo in particular frequency bands. In addition, a threshold of the non-linear processor may be adjustable, e.g., by a user, to denote a minimum signal level that can be suppressed by the non-linear processor. Existing non-linear processors in typical acoustic echo cancellation systems can only calculate a gain of either 0 or 1. That is, the gain in these existing non-linear processors may be calculated as 0 (e.g., residual echo is fully suppressed), or as 1 (e.g., no residual echo suppression occurs). However, full suppression of residual echo (e.g., when the gain is 0) may cause unintended attenuation of desired sound (e.g., near end voice) in certain situations.

The mask value may be generated as a value on a continuum between 0 and 1. The generated mask value may be used as a gain of the non-linear processor in order to make the gain more precise, which can result in more optimal suppression of residual echo and better overall acoustic echo cancellation. For example, desired sound captured by a microphone may not be unintentionally attenuated using a non-linear processor that has a more precise calculated gain.

Other systems and methods described herein can adjust a threshold of the non-linear processor when a loudspeaker is active. For example, when a microphone is physically close to a loudspeaker, there may be an unacceptable increase in the far end single talk leakage that cannot be suppressed by a typical non-linear processor in existing acoustic echo cancellation systems. Far end single talk describes a scenario when only the far end remote participant is speaking and the far end audio is captured by the microphone. However, far end single talk leakage can occur in situations when the microphone is physically close to the loudspeaker, such as when the far end audio may be captured by the microphone with a greater energy level that a typical non-linear processor cannot consistently suppress (particularly in low frequency sub-bands).

The threshold of the non-linear processor can be adjusted when the loudspeaker is active to help suppress far end single talk leakage. For example, the threshold of a lower frequency sub-band of a non-linear processor can be increased when the loudspeaker is active, particularly in situations where the loudspeaker and the microphone are physically proximate. Through use of the acoustic echo cancellation system and the non-linear processor systems and methods described herein, the removal of residual echo by the non-linear processor may be improved and the overall acoustic echo cancellation performance may be enhanced.

FIG. 1 is a schematic diagram of a communication system 100 for capturing sound from audio sources in an environment using a microphone 102 and presenting audio from a remote location using a loudspeaker 104. The communication system 100 may include an acoustic echo cancellation system 150 that includes an adaptive filter 106, an estimator 108, and a non-linear processor 110. A mask value may be generated by the non-linear processor 110 that can be used as the gain of the non-linear processor 110, which can result in more optimal suppression of residual echo and better overall acoustic echo cancellation, and is described in more detail below.

The communication system 100 may generate an echo-cancelled audio signal 113 using the acoustic echo canceller system. The echo-cancelled audio signal 113 may mitigate the sound received from the remote location that is played on the loudspeaker 104, and in particular, mitigate linear echo and residual echo that is sensed by the microphone 102. In

this way, the echo-cancelled audio signal 113 may be transmitted to the remote location without the undesirable echo of persons at the remote location hearing their own speech and sound.

Environments such as conference rooms may utilize the communication system 100 to facilitate communication with persons at the remote location, for example. The type of microphone 102 and its placement in a particular environment may depend on the locations of audio sources, physical space requirements, aesthetics, room layout, and/or other considerations. For example, in some environments, the microphone 102 may be placed on a table or lectern near the audio source. In other environments, the microphone 102 may be mounted overhead to capture the sound from the entire room, for example. The communication system 100 may work in conjunction with any type and any number of microphones 102.

Various components included in the communication system 100 may be implemented using software executable by one or more servers or computers, such as a computing device with a processor and memory, and/or by hardware (e.g., discrete logic circuits, application specific integrated circuits (ASIC), programmable gate arrays (PGA), field programmable gate arrays (FPGA), etc. In general, a computer program product in accordance with the embodiments includes a computer usable storage medium (e.g., standard random access memory (RAM), an optical disc, a universal serial bus (USB) drive, or the like) having computer-readable program code embodied therein, wherein the computer-readable program code is adapted to be executed by a processor (e.g., working in connection with an operating system) to implement the methods described herein. In this regard, the program code may be implemented in any desired language, and may be implemented as machine code, assembly code, byte code, interpretable source code or the like (e.g., via C, C++, Java, ActionScript, Python, Objective-C, JavaScript, CSS, XML, and/or others).

FIGS. 2-3 illustrate methods for utilizing the communication system 100 and the acoustic echo cancellation system 150. In particular, FIG. 2 illustrates a process 200 for determining an adaptation state of the adaptive filter 106 using an estimator 108. FIG. 3 illustrates a process 300 for generating a mask value that can be used as a gain of the non-linear processor 110, based on the adaptation state of the adaptive filter 106 and other signals, as described in more detail below.

Referring to FIG. 1, the microphone 102 may detect sound in the environment and convert the sound to an audio signal 103. In embodiments, the audio signal 103 from the microphone 102 may be processed by a beamformer (not shown) to generate one or more beamformed audio signals. Accordingly, while the systems and methods are described herein as using an audio signal 103 from microphone 102, it is contemplated that the systems and methods may also utilize any type of acoustic source, such as beamformed audio signals generated by a beamformer. In addition or alternatively, the audio signal 103 from the microphone 102 and the remote audio signal 101 may be converted into the frequency domain, in which case, the acoustic echo cancellation system 150 can operate in the frequency domain.

The adaptive filter 106 may process the remote audio signal 101 to generate a filtered remote audio signal 107 that is an estimate of the acoustic path of the remote audio signal 101, e.g., a model of the echo that will be detected by the microphone 102. In embodiments, the adaptive filter 106 may be a finite impulse response filter. The filtered remote audio signal 107 generated by the adaptive filter 106 may be

subtracted from the audio signal 103 of the microphone 102 at the summing point 105 to generate an initial echo-cancelled audio signal 111. Linear echo in the microphone audio signal 103 may be suppressed in the initial echo-cancelled audio signal 111.

As shown in the process 200 of FIG. 2 for determining an adaptation state of the adaptive filter 106, the estimator 108 may process the microphone audio signal 103 and the filtered remote audio signal 107 to determine the adaptation state of the adaptive filter 106. In some embodiments, there may be multiple microphones 102 with associated estimators 108. In other embodiments, there may be an estimator 108 for each of several frequency bands. At step 202, the estimator 108 can detect whether there is an active filtered remote audio signal 107. There may be an active filtered remote audio signal 107, for example, when there is activity on the remote audio signal 101, such as speech or other sound from the remote location that is subsequently filtered by the adaptive filter 106. If a filtered remote audio signal 107 is not detected at step 202 (“NO” branch of step 202), then the process 200 may remain at step 202 until a filtered remote audio signal 107 is detected.

However, if a filtered remote audio signal 107 is detected at step 202 (“YES” branch of step 202), then the process 200 continues to step 204. At step 204, the estimator 108 may measure the coherence between the filtered remote audio signal 107 and the microphone audio signal 103. The coherence is a measure of the relationship between the frequency content of the filtered remote audio signal 107 and the microphone audio signal 103 from the microphone 102. At step 206, the measured coherence can be output from the estimator 108 to the non-linear processor 110.

At step 208, it can be determined whether the echo return loss enhancement (ERLE) metric of the acoustic echo cancellation system 150 is greater than an upper hysteresis bound, such as 1 dB, for example. The ERLE metric is a measure of the performance of the overall acoustic echo cancellation system 150, and may indicate how much echo has been attenuated from the microphone audio signal 103. In particular, ERLE may be defined as the ratio of the summation of the input magnitude frequency bands (of the microphone audio signal 103) to the summation of the output magnitude frequency bands. For purposes of ERLE, the output signal may be measured after being processed by the non-linear processor 110, but before any noise reduction. If the ERLE metric is greater than the upper hysteresis bound at step 208 (“YES” branch of step 208), then at step 210, an intermediate variable indicating the convergence of the adaptive filter 106 may be updated to approach 1.0. In embodiments, the estimator 108 may utilize a convergence integrator to update the convergence variable to approach 1.0.

However, if the ERLE metric is not greater than the upper hysteresis bound at step 208 (“NO” branch of step 208), then the process 200 may continue to step 212. At step 212, it can be determined whether the ERLE metric of the acoustic echo cancellation system 150 is less than a lower hysteresis bound, such as -1 dB, for example. If the ERLE metric is less than the lower hysteresis bound at step 212 (“YES” branch of step 212), then at step 214, the intermediate variable denoting the convergence of the adaptive filter 106 may be updated to approach 0.0. In embodiments, the estimator 108 may utilize a convergence integrator to update the convergence variable to approach 0.0. If the ERLE metric is not less than the lower hysteresis bound at step 212 (“NO” branch of step 212), then the convergence variable is

not updated and the process 200 may return to step 202 for detecting a filtered remote audio signal 107.

From step 210 or step 214 based on the convergence variable being updated, the process 200 may continue to 5 compare the convergence variable to comparison thresholds A and B. The comparison thresholds A and B may be in the range of 0.0 to 1.0 and may be used to determine the adaptation state of the adaptive filter 106. At step 216, it may be determined whether the convergence variable is less than 10 a comparison threshold A, such as 0.25, for example. If the convergence variable is less than the predetermined threshold A at step 216 (“YES” branch of step 216), then at step 218, the adaptation state of the adaptive filter 106 may be assigned as “Diverged”. A “Diverged” adaptation state of the 15 adaptive filter 106 can indicate that the adaptive filter 106 has not yet identified the residual echo and is therefore not actively suppressing the residual echo.

However, if the convergence variable is not less than the 20 predetermined threshold A at step 216 (“NO” branch of step 216), then the process 200 continues to step 220. At step 220, it may be determined whether the convergence variable is less than a predetermined threshold B, such as 0.5, for example. If the convergence variable is less than the predetermined threshold B at step 220 (“YES” branch of step 220), then at step 222, the adaptation state of the adaptive filter 106 may be assigned as “Converging”. A “Converging” adaptation state of the adaptive filter 106 may indicate that the adaptive filter 106 has started to identify the residual echo and is suppressing at least part of the residual echo.

Finally, if the convergence variable is not less than the 25 predetermined threshold B at step 220 (“NO” branch of step 220), then the process 200 continues to step 224 where the adaptation state of the adaptive filter 106 may be assigned as “Converged”. A “Converged” adaptation state of the adaptive filter 106 may indicate that the adaptive filter 106 has identified the residual echo and is suppressing the residual echo.

FIG. 3 shows a process 300 for the non-linear processor 110 to generate a mask value that can be used as a gain of 40 the non-linear processor 110. The mask value may be generated to be a value on a continuum between 0 and 1, in embodiments. In the process 300, the non-linear processor 110 may generate a mask value based on several signals: the microphone audio signal 103 (from microphone 102), the 45 filtered remote audio signal 107 (from adaptive filter 106), whether the filtered remote audio signal has been detected (from the estimator 108), the coherence between the filtered remote audio signal 107 and the microphone audio signal 103 (from the estimator 108), the adaptation state of the adaptive filter 106 (from the estimator 108), and a threshold 50 of the non-linear processor 110. In embodiments, the threshold of the non-linear processor 110 may be set by a user by setting the level of the non-linear processor 110, such as through a graphical user interface or other control interface. The level of the non-linear processor 110 may be set to one of a number of preset settings, e.g., low, medium, or high. The threshold of the non-linear processor 110 may denote the minimum level of a signal that will be suppressed by the 55 non-linear processor 110, and may be used by the non-linear processor 110 in the comparison of the microphone audio signal 103 to the filtered remote audio signal 107 on a per sub-band basis.

At step 302, the mask value may be initialized, such as to 60 a value of one minus the coherence measurement that was performed at step 204 of the process 200 described above. The mask value may be initialized to this value due to the coherence measurement being naturally in the range of 0.0

to 1.0, which therefore allows the mask value to also be in the range of 0.0 to 1.0. A range of 0.0 to 1.0 may be an ideal range for an attenuation variable, in embodiments. In addition, the mask value may be initialized to one minus the coherence measurement because coherence and non-linear processing attenuation are directly related. In particular, when the coherence measurement is higher, then the attenuation by the non-linear processor 110 may also be higher.

At step 304, it can be determined whether an active filtered remote audio signal 107 has been detected. In embodiments, whether an active filtered remote audio signal 107 has been detected may have been determined at step 202 of the process 200 described above, and transmitted from the estimator 108 to the non-linear processor 110 for use at step 304. If an active filtered remote audio signal 107 has not been detected at step 304 ("NO" branch of step 304), then the process 300 may continue to step 306. At step 306, the mask value may be set to 1.0 and the state of the communication system 100 may be denoted as near end single talk, e.g., there is only near end activity and there is no far end activity (e.g., no activity on the remote audio signal 101). When the mask value is set to 1.0, there will be no change to the gain of the non-linear processor 110. The process 300 may continue to step 326 to set the final mask value, which is described in more detail below.

However, if an active filtered remote audio signal 107 has been detected at step 304 ("YES" branch of step 304), then the process 300 may continue to step 308. At step 308, it may be determined whether the adaptation state of the adaptive filter 106 is in a "Diverged" state, such as at step 218 of the process 200 described previously. If it is determined at step 308 that the adaptation state of the adaptive filter 106 is in a "Diverged" state ("YES" branch of step 308), then at step 310 the initialized mask value may be multiplied by a relatively small value (e.g., 0.01) to increase the attenuation of residual echo performed by the non-linear processor 110. The process 300 may continue to step 326 where the final mask value may be set. If it is determined at step 308 that the adaptation state of the adaptive filter 106 is not in a "Diverged" state ("NO" branch of step 308), then the process 300 may continue to step 312.

At step 312, it may be determined whether the adaptation state of the adaptive filter 106 is in a "Converging" state, such as at step 222 of the process 200 described previously. If it is determined at step 312 that the adaptation state of the adaptive filter 106 is in a "Converging" state ("YES" branch of step 312), then the process 300 may continue to step 314. At step 314, it may be determined whether the level of the microphone audio signal 103 is greater than the level of the filtered remote audio signal 107 plus a preset amount (e.g., by a factor of 4 over the level of the filtered remote audio signal 107). The preset amount utilized in the comparison may be selected to have a comparison that is higher than the thresholds used for levels (e.g., low, medium, or high) of the non-linear processor 110 when the adaptation state of the adaptive filter 106 is in a "Converged" state. In this way, a higher likelihood of suppression of residual echo may occur when the adaptation state of the adaptive filter 106 is in a "Converging" state. This is in contrast to when the adaptation state of the adaptive filter 106 is in a "Converged" state, which is when it is less desirable to perform suppression.

If the level of the microphone audio signal 103 is not greater than the level of the filtered remote audio signal 107 plus the preset amount at step 314 ("NO" branch of step 314), then the process 300 may continue to step 310 so that the initialized mask value may be multiplied by a relatively small value (e.g., 0.01) to increase the attenuation of residual

echo performed by the non-linear processor 110. However, if the level of the microphone audio signal 103 is greater than the level of the filtered remote audio signal 107 plus the preset amount at step 314 ("YES" branch of step 314), then the process 300 may continue to step 316 to multiply the initialized mask value by a relatively large value (e.g., 2.0) to decrease the attenuation of residual echo performed by the non-linear processor 110. From step 310 or step 316, the process 300 may continue to step 326 where the final mask value may be set.

Returning to step 312, it may be determined that the adaptation state of the adaptive filter 106 is not in a "Converging" state ("NO" branch of step 312). In this case, the process 300 may continue to step 318 where the adaptation state of the adaptive filter 106 is determined to be in a "Converged state", such as at step 224 of the process 200 described previously. This is because there are three possible adaptation states of the adaptive filter 106 that can be assigned in the process 200. As such, in the process 300, if it has been determined that the adaptation state of the adaptive filter 106 is not in a "Diverged" state (at step 308) or a "Converging" state (at step 312), then the adaptation state of the adaptive filter 106 is in a "Converged" state (at step 318).

At step 320, it may be determined whether the level of the microphone audio signal 103 is greater than the level of the filtered remote audio signal 107 plus the threshold of the non-linear processor 110. If the level of the microphone audio signal 103 is greater than the level of the filtered remote audio signal 107 plus the threshold of the non-linear processor 110 at step 320 ("YES" branch of step 320), then at step 322, the mask value may be set to 1.0 and the state of the communication system 100 may be denoted as double talk, e.g., there is simultaneous near end activity and far end activity. When the mask value is set to 1.0, there will be no change to the gain of the non-linear processor 110.

However, if the level of the microphone audio signal 103 is not greater than the level of the filtered remote audio signal 107 plus the threshold of the non-linear processor 110 at step 320 ("NO" branch of step 320), then at step 324, the initialized mask value may be multiplied by a relatively small value (e.g., 0.01) to increase the attenuation of residual echo performed by the non-linear processor 110. In addition, the state of the communication system 100 may be denoted as far end single talk, e.g., there is only far end activity and there is no near end activity. From step 322 or step 324, the process 300 may continue to step 326 where the final mask value may be set. It should be noted that the values that the initialized mask value may be multiplied by (e.g., at steps 310, 316, and 324) are exemplary and may be other appropriate values.

The process 300 may reach step 326 following each of steps 306, 310, 316, 322, or 324, as discussed above. At step 326, the final mask value may be set by the process 300 to be constrained between 0.0 and 1.0 based on the following limitations: (1) the minimum of 1.0 and the current mask value, and (2) the maximum of 0.0 and the current mask value. The current mask value utilized in step 326 may be the mask value that was set at step 306, 310, 316, 322, or 324. For example, if the current mask value has been set to 1.0 (e.g., at step 306 or step 322), then at step 326 the final mask value will be set to 1.0 since 1.0 is: (1) the minimum of 1.0 and the current mask value (1.0) and (2) the maximum of 0.0 and the current mask value (1.0). In embodiments, the final mask value may be set at step 326 according to different limitations.

In this way, the final mask value may be set by the process 300 to a value in a continuum between 0.0 and 1.0, which allows the gain of the non-linear processor 110 to also be set to a more precise value in a continuum between 0.0 and 1.0. In particular, the final mask value may be output from the non-linear processor 110 and be used as the gain of the non-linear processor 110. The final mask value may be multiplied at combining point 112 with the initial echo-cancelled signal 111 to suppress any residual echo that has not been fully eliminated at the summing point 105, and to generate the final echo-cancelled audio signal 113.

FIG. 4 is a schematic diagram of a communication system 400 for capturing sound from audio sources in an environment using a microphone 102 and presenting audio from a remote location using a loudspeaker 404. The communication system 400 may include an acoustic echo cancellation system 450 that includes an adaptive filter 106, an estimator 108, and a non-linear processor 410. The communication system 400 may be similar to the communication system 100 of FIG. 1 as described above, except that there is communication between the loudspeaker 404 and the non-linear processor 410 (via a signal or message 414) to enable adjustment of the threshold of the non-linear processor 410 when the loudspeaker 404 is active. For simplicity, descriptions of the functions of the adaptive filter 106 and the estimator 108 will not be repeated here. It should be noted that while the communication system 400 shown in FIG. 4 has the ability to generate a mask value, as described previously, any suitable acoustic cancellation system having a non-linear processor may be able to use communication between the loudspeaker 404 and the non-linear processor 410 for adjustment of the threshold of the non-linear processor 410 when the loudspeaker 404 is active.

The threshold of the non-linear processor 410 may be adjusted when the loudspeaker 104 is active to help in suppressing far end single talk leakage. In particular, the threshold of the lowest frequency sub-band can be increased in the non-linear processor 410 when the loudspeaker 404 is active. For example, the lowest frequency sub-band may cover the range of 0-375 Hz, which can include the frequency range where most far end single talk leakage occurs. This adjustment of the threshold of the lowest frequency sub-band may be useful when the microphone 102 and the loudspeaker 404 are in close physical proximity, such as when the microphone 102 and the loudspeaker 404 are housed in the same device. In embodiments, the microphone 102 and the loudspeaker 404 may be in networked communication with one another.

The communication between the loudspeaker 404 and the non-linear processor 410 may include a signal or message 414 from the loudspeaker 404 to indicate that the loudspeaker 404 is active. In embodiments, a processor (not shown) in the communication system 400 may send the signal or message 414 to the non-linear processor 410 to indicate that the loudspeaker 404 is active.

FIGS. 5-6 illustrate embodiments of methods for utilizing the communication system 400 and the acoustic echo cancellation system 450 where the threshold of the non-linear processor 410 can be adjusted. FIG. 5 illustrates a process 500 for adjusting a threshold of the non-linear processor 410 of FIG. 4 based on whether a state of the loudspeaker 404 has changed and whether the loudspeaker 404 is active. FIG. 6 illustrates a process 600 for adjusting a threshold of the non-linear processor 410 of FIG. 4 based on whether a level of the non-linear processor 410 has changed and whether the

loudspeaker 404 is active. In embodiments, the process 500 and the process 600 can be executed independently and/or simultaneously.

The level of the non-linear processor 410 may determine the threshold of the non-linear processor 410. For example, the level of the non-linear processor 410 may be selected by a user to be low, medium, or high. For example, the threshold of the non-linear processor 410 when the level of the non-linear processor 410 is set to low may be lower than the threshold of the non-linear processor 410 when the level of the non-linear processor 410 is set to medium.

Referring to FIG. 5, the threshold of the non-linear processor 410 can be adjusted based on whether a state of the loudspeaker 104 has changed and whether the loudspeaker 404 is active. At step 502, it can be determined whether the loudspeaker 404 has changed its state. The loudspeaker 404 may be considered as changing its state if it becomes active (e.g., playing sound) or becomes inactive (e.g., stops playing sound). The non-linear processor 410 may detect that the loudspeaker 404 has changed its state via a message 414 sent from the loudspeaker 404. If it is determined that the loudspeaker 404 has not changed its state at step 502 ("NO" branch of step 502), then the process 500 may remain at step 502. However, if it is determined that the loudspeaker 404 has changed its state at step 502 ("YES" branch of step 502), then the process 500 may continue to step 504.

At step 504, it can be determined whether the loudspeaker 404 is active, for example, if loudspeaker 404 has been connected to play the far end remote audio signal 101. The non-linear processor 410 may detect that the loudspeaker 404 is active or inactive via a message 414 sent from the loudspeaker 404. If it is determined that the loudspeaker 404 is active at step 504 ("YES" branch of step 504), then at step 506, the threshold of the lowest frequency sub-band can be increased in the non-linear processor 410 by a predetermined amount (e.g., 5 dB) above the current level default. However, if it is determined that the loudspeaker 404 is inactive at step 504 ("NO" branch of step 504), then at step 508, the threshold of the lowest frequency sub-band can be set to the current level default. The current level default may be the threshold of the lowest frequency sub-band based on the current setting of the level of the non-linear processor 410.

Referring to FIG. 6, the threshold of the non-linear processor 410 of FIG. 4 can be adjusted based on whether a level of the non-linear processor 410 has changed and whether the loudspeaker 404 is active. At step 602, it can be determined whether a level of the non-linear processor 410 has changed. The level of the non-linear processor 410 may be changed, for example, by a user through a graphical user interface, command line interface, or other control interface. If it is determined that the level of the non-linear processor 410 has not changed at step 602 ("NO" branch of step 602), then the process 600 may remain at step 602. However, if it is determined that the level of the non-linear processor 410 has changed at step 602 ("YES" branch of step 602), then the process 600 may continue to step 604.

At step 604, it can be determined whether the loudspeaker 404 is active, such as if it has been connected to play the far end remote audio signal 101. The non-linear processor 410 may detect that the loudspeaker 404 is active or inactive via a message (e.g., message 414 of FIG. 4) transmitted from the loudspeaker 404. If it is determined that the loudspeaker 404 is active at step 604 ("YES" branch of step 604), then at step 606, the threshold of the lowest frequency sub-band can be increased in the non-linear processor 410 by a predetermined amount (e.g., 5 dB) above the current level default.

11

However, if it is determined that the loudspeaker 404 is inactive at step 604 ("NO" branch of step 604), then at step 608, the threshold of the lowest frequency sub-band can be set to the current level default.

Any process descriptions or blocks in figures should be understood as representing modules, segments, or portions of code which include one or more executable instructions for implementing specific logical functions or steps in the process, and alternate implementations are included within the scope of the embodiments of the invention in which functions may be executed out of order from that shown or discussed, including substantially concurrently or in reverse order, depending on the functionality involved, as would be understood by those having ordinary skill in the art.

The description herein describes, illustrates and exemplifies one or more particular embodiments of the invention in accordance with its principles. This description is not provided to limit the invention to the embodiments described herein, but rather to explain and teach the principles of the invention in such a way to enable one of ordinary skill in the art to understand these principles and, with that understanding, be able to apply them to practice not only the embodiments described herein, but also other embodiments that may come to mind in accordance with these principles. The scope of the invention is intended to cover all such embodiments that may fall within the scope of the appended claims, either literally or under the doctrine of equivalents.

It should be noted that in the description and drawings, like or substantially similar elements may be labeled with the same reference numerals. However, sometimes these elements may be labeled with differing numbers, such as, for example, in cases where such labeling facilitates a more clear description. Additionally, the drawings set forth herein are not necessarily drawn to scale, and in some instances proportions may have been exaggerated to more clearly depict certain features. Such labeling and drawing practices do not necessarily implicate an underlying substantive purpose. As stated above, the specification is intended to be taken as a whole and interpreted in accordance with the principles of the invention as taught herein and understood to one of ordinary skill in the art.

This disclosure is intended to explain how to fashion and use various embodiments in accordance with the technology rather than to limit the true, intended, and fair scope and spirit thereof. The foregoing description is not intended to be exhaustive or to be limited to the precise forms disclosed. Modifications or variations are possible in light of the above teachings. The embodiment(s) were chosen and described to provide the best illustration of the principle of the described technology and its practical application, and to enable one of ordinary skill in the art to utilize the technology in various embodiments and with various modifications as are suited to the particular use contemplated. All such modifications and variations are within the scope of the embodiments as determined by the appended claims, as may be amended during the pendency of this application for patent, and all equivalents thereof, when interpreted in accordance with the breadth to which they are fairly, legally and equitably entitled.

The invention claimed is:

1. A device, comprising:

at least one processor configured to:

adjust a low band threshold of a non-linear processor based on whether a loudspeaker is active; estimate, with an estimator, an adaptation state of an adaptive filter based on a microphone signal and a filtered remote audio signal; and

12

generate, with the non-linear processor, a mask value usable as a gain of the non-linear processor, wherein the generation of the mask value is based on: the adaptation state of the adaptive filter, the microphone signal, and the filtered remote audio signal.

2. The device of claim 1, where the at least one processor is further configured to:

adaptively filter, with the adaptive filter, a remote audio signal to the filtered remote audio signal; multiply the mask value with an initial echo-cancelled audio signal to generate a final echo-cancelled audio signal; and output the final echo-cancelled audio signal.

3. The device of claim 1, wherein the at least one processor is configured to estimate the adaptation state of the adaptive filter by:

generating, with a convergence integrator, a convergence variable indicating a convergence of the adaptive filter; and

determining the adaptation state of the adaptive filter using the estimator based on a comparison of the convergence variable to a predetermined threshold.

4. The device of claim 3, wherein the at least one processor is configured to generate the convergence variable with the convergence integrator based on a comparison of a performance metric to one or more thresholds, and wherein the performance metric is derived from the microphone signal and the filtered remote audio signal.

5. The device of claim 1, wherein the at least one processor is configured to generate the mask value based on the adaptation state of the adaptive filter, a coherence of the microphone signal and the filtered remote audio signal, and a comparison of the microphone signal and the filtered remote audio signal with respect to a threshold of the non-linear processor.

6. The device of claim 5, wherein the coherence of the microphone signal and the filtered remote audio signal comprises a frequency domain correlation of the microphone signal and the filtered remote audio signal.

7. The device of claim 1, wherein the at least one processor is further configured to initialize the mask value with the estimator based on a coherence of the microphone signal and the filtered remote audio signal.

8. The device of claim 1, wherein the at least one processor is configured to generate the mask value with the non-linear processor by setting the mask value based on the adaptation state of the adaptive filter.

9. The device of claim 8, wherein the at least one processor is configured to generate the mask value with the non-linear processor by setting the mask value based on: the adaptation state of the adaptive filter, and a comparison of the microphone signal and the filtered remote audio signal with respect to a threshold of the non-linear processor.

10. The device of claim 1, wherein the at least one processor is configured to adjust the low band threshold of the non-linear processor when the loudspeaker is active such that far end single talk leakage is minimized.

11. The device of claim 1, wherein the at least one processor is configured to adjust the low band threshold of the non-linear processor further based on one or more of whether a state of the loudspeaker has changed or whether a level of the non-linear processor has been changed.

12. The device of claim 1, wherein the at least one processor is configured to adjust the low band threshold of the non-linear processor by:

increasing the low band threshold of the non-linear processor when the loudspeaker is active; and

13

decreasing the low band threshold of the non-linear processor when the loudspeaker is not active.

13. A method, comprising:

adjusting a low band threshold of a non-linear processor based on whether a loudspeaker is active;

estimating an adaptation state of an adaptive filter based on a microphone signal and a filtered remote audio signal; and

generating a mask value usable as a gain of the non-linear processor, wherein the generation of the mask value is based on: the adaptation state of the adaptive filter, the microphone signal, and the filtered remote audio signal.

14. The method of claim 13, further comprising:

adaptively filtering a remote audio signal to the filtered remote audio signal;

multiplying the mask value with an initial echo-cancelled audio signal to generate a final echo-cancelled audio signal; and

outputting the final echo-cancelled audio signal.

15. The method of claim 13, wherein estimating the adaptation state of the adaptive filter comprises:

generating a convergence variable indicating a convergence of the adaptive filter; and

14

determining the adaptation state of the adaptive filter based on a comparison of the convergence variable to a predetermined threshold.

16. The method of claim 13, wherein generating the mask value comprises generating the mask value based on the adaptation state of the adaptive filter, a coherence of the microphone signal and the filtered remote audio signal, and a comparison of the microphone signal and the filtered remote audio signal with respect to a threshold of the non-linear processor.

17. The method of claim 13, wherein adjusting the low band threshold of the non-linear processor is further based on one or more of whether a state of the loudspeaker has changed or whether a level of the non-linear processor has been changed.

18. The method of claim 13, wherein adjusting the low band threshold of the non-linear processor comprises:

increasing the low band threshold of the non-linear processor when the loudspeaker is active; and

decreasing the low band threshold of the non-linear processor when the loudspeaker is not active.
